CADDY CART OR THE LIKE

Arlo R. Jordan, 1909 6th Ave., NE., Austin, Minn.

Filed Jan. 2, 1962, Ser. No. 68,135

Term of patent 14 years

(Cl. D14—3)

The dominant features of my design reside in the portions shown in full lines.

I claim:

The ornamental design for a caddy cart or the like, substantially as shown and described.
